HARRY C. GAMMETER, OF CLEVELAND, OHIO, ASSIGNEE TO THE AMERICAN MULTIGRAPH COMPANY, OF CLEVELAND, OHIO, A CORPORATION OF OHIO.

PAPER-FEEDING MECHANISM.

1,143,963.

Specification of Letters Patent. Patented Aug. 3, 1915.

Application filed June 16, 1914. Serial No. 845,426.

To all whom it may concern:

Be it known that I, HARRY C. GAMMETER, a citizen of the United States, residing at Cleveland, in the county of Cuyahoga and State of Ohio, have invented a certain new and useful Improvement in Paper-Feeding Mechanism, of which the following is a full, clear, and exact description, reference being had to the accompanying drawings.

10 The object of this invention is to provide a very simple paper feeding mechanism for small rotary printing machines—preferably such machines as may be driven by hand and are suitable for use in an office.

15 The invention is hereinafter more fully explained and its essential characteristics are set out in the claims.

In the drawings, Figure 1 is a vertical cross section of a rotary printing machine equipped with my paper feeding mechanism; Fig. 2 is an enlarged section of a portion of the feeding mechanism shown in Fig. 1 in its non-feeding position; Fig. 3 is an enlarged front elevation of the machine shown in Fig. 1, somewhat broken away; Fig. 4 is a plan of a portion of the machine just above the platen and lower feeding roller; Fig. 5 is an end view of the machine looking from the right hand end of Fig. 3; Fig. 6 is a partial end view of the opposite end of the machine.

The frame of the machine shown consists of a pair of upright end plates 10 and 11 and suitable cross members, as the castings 12 and 13 between the end plates and secured thereto by suitable screws. Journaled in the end plates is a shaft 15 on which is mounted, between the end plates, a drum 16. This drum has suitable means for carrying a printing surface, as, for example, the parallel rails 17 which are adapted to loosely confine between them short type grooved on their opposite sides. The drum is removably clamped to the shaft by suitable means, as, for example, the set screws 20 in bosses 21 carried by the end portions 22 of the drum. A suitable crank 27, or other means connected with the shaft, provides for rotating the drum as desired. The removal of the screws 20 allows the drum to be removed from between the frame plates, and another drum having mounted on it a different printing form may then be conveniently substituted for the removed drum.

Beneath the drum is a rotary platen 30 which is journaled on a shaft 31 having eccentric portions mounted in the frame plates 10 and 11. On one end of this shaft is a lever 33 by which it may be turned to change the presentation of the platen to the printing drum. This lever is locked in active or non-active position by a suitable detent 34 thereon, which engages a depression in the arcual plate 35 which is adjustably clamped on the end member 11, by the thumb screw 37. The other end of the platen shaft is preferably journaled in a bushing adjusted by a lever 38 which provides for accurate alinement of the platen with the printing drum. On the platen shaft is a gear 40 suitably connected with the platen, as, for example, by an Oldham coupling 41, this gear meshing with a gear 43 on the printing drum.

Meshing with the platen gear 40 is an idle pinion 50 which meshes with a pinion 51 on a shaft 52 which carries a series of feed rolls 53. These rolls are accordingly continuously rotated in a feeding direction 57 when the drum is being rotated. Above the feed rolls 53 is a roller 55 mounted between ears 56 on the rear end of a curved guard plate 57 which is pivoted by means of forward ears 58 near its ends. Extending upwardly from the curved guard plate 57 is an arm portion 59 which carries a roller 60. This roller is designed to engage with a cam 63 formed on a ring 64 which surrounds a hub portion 65 of the gear 43 and lies alongside of the teeth of that gear.

The action of the cam 63 on the roller 60 lifts the roller 55 away from the roller 53 so that these rollers are out of feeding co-action. This same movement swings upwardly into the path of the paper suitable stop hooks 70. These hooks are in the form of sheet metal members having down-turned ears 71 (Fig. 2) which surround an angular shaft 72. This shaft is provided near one end with an arm 73 which carries a set screw 74 adapted to abut a lug 75 on the under side of one of the arms 57. A coiled spring 78 surrounds the shaft 72 and tends to raise the fingers 70. These fingers stand between the rollers 53 and these rollers and the fingers alternately project upwardly between suitable rearward extensions 80 of a paper table 81. There may be a forward removable extension 83 of this table.

With the structure described, when the drum is being rotated, the paper is fed by hand, a sheet at a time, along the tables 83 and 81 against the stop fingers 70. Then, 5 at the proper time, the cam 63 travels off of the roller 60 and a spring 85 (Fig. 3), connected with one of the arms 57, swings the roller 55 downwardly into coaction with the rollers 53 and at the same time turns the 10 rock shaft 72 to depress the hooks 70 so that the paper is simultaneously engaged by the feed rollers and freed by the dropping hooks and is thus fed between the drum and platen.

15 The time of feeding is determined by the position of the cam 63 on the drum. This cam ring is normally clamped by set screws 87 (Fig. 3) which clamp the gear 43 in fixed position on the drum. When it is desired to change the position of the cam, the 20 drum is turned so as to bring the set screws 87 opposite openings 88 in the frame plate 11, and then a screw driver inserted through these openings loosens the screws so that it 25 is possible to shift the gear and cam. This shifting may be conveniently accomplished by locking the gear and turning the drum by its shaft. To provide for this locking I mount a bell crank 89 on the frame which 30 may be turned to cause its nose to project between the teeth of the gear. This gear lock may also be employed to hold the drum in stationary position when sliding lines of type into the channels between the rails. 35 The drawing shows a delivery roll 90 geared with the platen and surmounted by delivery rolls 91 in arms 92 carried by a rod 93, and the drawing shows a stripper 95 extending from the rod 93 forwardly between the drum and platen and above the 40 paper feeding device. The ejector or delivery mechanism, however, is not claimed in this application, but in a co-pending application of mine, filed contemporaneously 45 herewith.

Any suitable means may be employed to ink the type carried by the drum. I have illustrated for this purpose a fountain or self-supply roller 96 loosely mounted in 50 ways in the frame plate and bearing upon a form roller 97 which contacts with the type on the drum. Fig. 1 also shows studs 98 which (with studs at the other end) may carry spools about which are wound the ends 55 of an inking ribbon which extends about the drum.

It will be seen that the printing machine shown in the drawings is very simple and cheap in construction, and, at the same time, 60 produces a complete printing machine, it being only necessary to rotate the drum and feed paper to the feed rollers.

Having thus described my invention, what I claim is:

65 1. In a paper feeding device, the combination of a pair of rotatable rollers, and a pivoted yoke having ears at its ends carrying one of the rollers, said yoke extending along the forward edge of the paper and being deflected away from the path of the paper so that it forms a guide for paper advanced to the rollers.

2. The combination of a pair of upright frame plates, a horizontal printing roller and platen extending between said plates, a feed roller extending between said plates and mounted on a stationary axis, a guide plate extending between the frame plates and pivoted to them, and a second feed roller carried by the guide plate.

3. The combination, with a pair of upright frame plates, of a rotary printing couple carried by and between said plates, an under feed roller geared with the couple, an upper feed roller, a plate having forward ears by which it is pivoted to the frame plates, and having rearward ears by which it carries said upper feed roller.

4. The combination of a stationarily mounted feed roller, a bodily movable feed roller, a curved guide plate as long as the width of the paper to be fed, ears on the rear end of said guide plate carrying the journals of the bodily movable roller, and other ears on the guide plate by which it is pivoted.

5. The combination, with a printing drum and a roller platen, of a bodily movable feed roller, a guide plate of substantially the length of the platen extending parallel with it and having rearwardly extending ears at its ends carrying the journals of the bodily movable feed roller, means pivotally mounting the guide plate, an arm rigid with the guide plate, and a cam mounted on the printing drum for operating the arm.

6. The combination, with a pair of feed rollers, one of which is bodily movable and as long as the maximum width of paper which may be fed, a longitudinal guide plate carrying the bodily movable feed roller and pivotally mounted, a stop finger, mechanism for automatically rocking the stop finger when the guide plate is rocked, and means for rocking the guide plate to bring the roller into action and to withdraw the stop finger.

7. The combination of a rotary printing drum, a rotary coating platen, a gear on the drum, a meshing gear connected with the platen, a paper feeding mechanism, a cam mounted on the gear on the drum for controlling the paper feeding mechanism, and means for turning the drum, and a device adapted to engage between teeth on the gear on the drum for holding it in place.

8. The combination of a rotary printing drum, a gear ring thereon movable about the drum, means for locking the said gear in place on the drum, means for turning the

drum means for holding the gear independently of the drum whereby the drum may be turned within the gear to change the relative position of the gear, paper feeding mechanism, and a cam for controlling the same adjustable with said gear.

9. The combination of a pair of upright frame plates, a shaft journaled therein, a rotary printing drum on said shaft, a gear ring movable about the drum, a screw for locking the gear in place on the drum, there being an opening through one of the frame

plates to provide access to said screws, means for turning the drum, means for holding the gear independently of the drum, paper feeding mechanism, and a cam for controlling the same adjustable with said gear. 15

In testimony whereof, I hereunto affix my signature in the presence of two witnesses.

HARRY C. GAMMETER.
